YARN GUIDING DEVICE

Linton L. Jones, Greenville, S. C.

Application August 17, 1945, Serial No. 611,093

11 Claims. (Cl. 57—112)

My invention relates to twisting or spinning machines, and has particular reference to a yarn guiding device for use upon such machines, and adapted for other uses.

An important object of the invention is to provide a yarn guiding device for use on a twisting machine which will eliminate the conventional flyer.

A further object of the invention is to provide a device of the above mentioned character which may be used to eliminate the conventional traveler on a spinning or twisting machine.

A further object of the invention is to provide a device of the above mentioned character which is adjustable to obtain the selected tension on the yarn.

A further object of the invention is to provide a device of the above mentioned character wherein an annular floating member engages with the yarn, taking the place of the usual flyer or traveler.

A further object of the invention is to provide a device of the above mentioned character requiring no lubrication when in use, thus eliminating the disadvantage of the oil being applied to the yarn.

Other objects and advantages of the invention will be apparent during the course of the following description.

In the accompanying drawings forming a part of this application and in which like numerals are employed to designate like parts throughout the same,

Figure 1 is a side elevation of a yarn guiding device embodying my invention as applied to a twisting machine.

Figure 2 is a plan view of the same, parts in section,

Figure 3 is a transverse section taken on line 3—3 of Figure 2, parts in elevation,

Figure 4 is an exploded perspective view of the device,

Figure 5 is an enlarged transverse section taken on line 5—5 of Figure 2,

Figure 6 is a side elevation of a yarn guiding device embodying a second form of the invention,

Figure 7 is a transverse section taken on line 7—7 of Figure 8,

Figure 8 is a plan view of the device,

Figure 8a is a fragmentary perspective view of a modified form of yarn guiding ring,

Figure 9 is an exploded perspective view of the second form of yarn guiding device,

Figure 10 is a transverse section taken on line 10—10 of Figure 8,

Figure 11 is a fragmentary plan view of the outer casing, showing a modified form of slit, and

Figure 12 is a section taken on line 12—12 of Figure 11.

In the drawings, wherein for the purpose of illustration is shown a preferred embodiment of my invention, the numeral 15 designates a vertical rotary spindle of a twisting machine, driven by any suitable means. This spindle carries the spool 16 of yarn. The spindle 15 is mounted upon the spindle swing 17, and a vertical post 18 is rigidly mounted upon the spindle swing, adjacent to each spool 16.

The numeral 19 designates a yarn guiding device as a whole, arranged adjacent to the top end of each spool 16, and the top end of the spool projects into this yarn guiding device for a short distance. This yarn guiding device takes the place of the conventional flyer. The yarn guiding device comprises a yarn guiding ring 20, which is stationary in use. This yarn guiding ring is closed or free from any slit and is preferably formed of steel but may be made of any other suitable material, and is preferably polished so that the yarn will slide freely thereon. The device 19 further comprises a floating

30 annular member or casing 21, including companion upper and lower annular sections 22, which are identical. The annular sections comprise outer opposed annular jaws 23, having their outer edges separate and spaced, as shown. These outer edges are preferably flared, as shown. These jaws are preferably formed of steel or any other suitable material, and the outer edges of the jaws are preferably polished.

35 The jaws 23 have openings 23' formed therein so that the yarn may be conveniently passed about the yarn guiding ring 20. Preferably formed integral with the annular jaws 23 at their inner edges are horizontal annular webs 24, carrying opposed jaws 25 at their inner edges.

40 The annular horizontal webs 24 are connected by pins 25', passing through openings 26 formed therein. Each pin is screw threaded at its opposite ends for receiving nuts 27. Each pin 25' carries washers 28, disposed inwardly of the webs 24 and having reduced extensions 29, to enter a compressible coil spring 30. The reduced extensions retain the coil spring spaced from the pin 25. The springs 30 tend to spread the horizontal webs 24, and these webs are drawn together by manipulating the nuts 27, as is obvi-

ous. The jaws 25 receive between them an inner connecting ring 31 and the jaws 25 clamp against the connecting ring 31. The outer jaws 23 are curved in vertical cross section and are substantially concentric with the face of the yarn guiding ring 20, which is circular in cross section, but the jaws 23 are formed on a larger radius than the yarn guiding ring 20, affording a space between the jaws 23 and yarn guiding ring 20. The yarn 16' is passed over the outer edges of the jaws 23 and upon the inner side of the yarn guiding ring 20. By manipulating the nuts 27, the jaws 23 may be brought together, thus reducing the space between these jaws and the yarn engaging ring 20 and thereby regulating the tension of the yarn, by increasing the area of contact between the yarn and the yarn guiding ring 20. This adjustment also compensates for yarns of different thickness.

Rigidly connected with the yarn guiding ring 20 is a radially extending rod 32. This rod is arranged adjacent to one end of a sleeve 33, having pairs of horizontal and vertical notches 34 and 35 formed therein, to receive the rod 32. The sleeve 33 receives a pin 36, having a head 37 upon one end. The opposite end of the pin 36 is screw threaded, as shown at 38, for engagement with a nut 39. A compressible coil spring 40 is arranged within the sleeve 33 and surrounds the pin 36 and engages with the head 37 and a shoulder 41, arranged within the sleeve 33 near its forward end. The pin 36 has a transverse slot 42 in its screw threaded end and the rod 32 extends through this transverse slot. The sleeve 33 is rigidly mounted upon a coupling 43, in turn rigidly mounted upon the vertical post 18. By adjusting the nut 39, the tension of the spring 40 may be regulated and the pin 36 and associated elements form a pivot for the rod 32, whereby the rod 32 may be swung to the horizontal or vertical position and held in such position against accidental displacement.

The operation of the device is as follows.

The yarn guiding device 19 is positioned adjacent to the upper end of the spool, so that the top of the spool passes into the same. The yarn guiding ring 20 is horizontally arranged and the annular member or casing 22 is also horizontal. The yarn 16' is passed over the outer edges of the jaws 23 and about the inner side of the yarn guiding ring 20, and passes above the spool 16, to be rewound upon another spool. Due to the rotation of the spool 16, the yarn slidably engaging the yarn guiding ring 20 will freely travel around the stationary yarn guiding ring and will also travel circumferentially about the casing or annular member 23. This casing or annular member floats in operation. The yarn guiding device may be used in a twisting machine to remove the yarn from the spool or to apply the yarn to the spool. The yarn guiding device may be used in connection with spools, bobbins, quills, spindles or other devices.

In Figures 6-12 inclusive, I have shown a second form of yarn guiding device embodying my invention. In these figures, the numeral 44 designates a stationary annular member or casing including upper and lower annular sections 45. These sections include inner opposed jaws 46, which are curved in vertical cross section. The free edges of these jaws are preferably flared. These jaws are preferably formed of steel, but may be formed of any suitable material, and the outer edges of these jaws are preferably polished. At their outer edges, these jaws have

horizontal annular webs 47, preferably formed integral therewith. At the outer edges of the horizontal webs 47 are opposed jaws 48, preferably integral therewith, and curved in vertical cross section. The horizontal webs 47 are adjustably connected by the pins 25', described in connection with the first form of the invention, and the same springs 30 are employed. By manipulating the nuts 27, the webs 47 may be drawn together and the outer jaws 48 clamped to a connecting ring 49, having an opening 50 formed therein. The rod 32 is rigidly connected with the connecting ring 49 and engages the same pin 36, described in connection with the first form of the invention. The rod 32 is therefore adapted to be swung to horizontal and vertical positions and to be held in such positions against displacement.

Arranged between the jaws 46 is a floating yarn guiding ring 51, which is preferably formed of steel but may be formed of any suitable material, and the ring 51 is polished so that the yarn will not have undue frictional engagement therewith. This ring 51 is continuous and free from any slit. The jaws 46 are curved in vertical cross section and the floating ring 51 is circular in vertical cross section, and the jaws 45 are formed upon a larger radius than the ring 51, thereby affording a space between these jaws and the ring 51 for the passage of the yarn. The yarn 16' from the spool is passed about the inner edges of the jaws 46 and about the outer side of the floating yarn guiding ring 51 and then extends above the yarn guiding device to be wound upon the next spool. The floating ring 51 may be formed solid, as shown in Figure 5, or I may employ a hollow floating ring 51', Figure 5a. When a hollow floating ring is employed, the inner side is preferably cut away to render the same light. In this form of the invention, the yarn engaging ring 51 floats, while the outer annular member or casing 46 is stationary.

The outer annular member or casing 46 may not be provided with the openings 23', to facilitate threading the yarn about the yarn engaging ring 51. For this reason, the casing 46 may have a transverse diagonal slit 52, so that the yarn may be threaded through this slit about the outer side of the floating ring 51 and brought into engagement with the inner edges of the jaws 46. The pull upon the yarn when being wound upon the spool above the yarn guiding device is radially inwardly and there will be little tendency for the yarn to reenter the slit 52. However, the inclination of the slit 52 with respect to the rotation of the yarn will prevent the yarn re-entering the slit, and this relative inclination is maintained by inverting the yarn guiding device, for the right or left twist upon the yarn. In Figure 8, the edges of the slit 52 are arranged in opposed relation. I contemplate reducing the thickness of the casing 46 adjacent to the slit, forming thin extensions 54, and having these extensions overlapping, as shown in Figure 12, thereby further eliminating any tendency for the yarn to escape through the slit. If the casing 46 is provided with the openings 23', as described in connection with the first form of the invention, the slit 52 may be omitted.

The operation of the second form of the invention is as follows.

The yarn 16' is passed about the inner edges of the jaws 45 and about the outer side of the floating ring 51 and extends to the spool above the guide device, upon which the yarn is wound.

The yarn guiding ring 51 floats and the yarn travels freely circumferentially of this floating ring 51. By adjusting the nuts 21, the jaws 46 may be drawn together and the tension increased upon the yarn, by increasing the area of contact between the yarn and the floating ring.

While I have shown my yarn engaging device as used in connection with a winding machine for dispensing with the conventional flyer, yet it is obvious that it may be used in connection with a spinning frame for dispensing with the conventional traveler. The device is not restricted in use in connection with a twisting machine or a spinning frame, but may be used in various other places wherein it is desired to guide yarn.

As is well known, some yarn is twisted right, while others are twisted left, and my yarn guiding device takes care of this situation, as it may be readily inverted. The device is inverted by slightly loosening the nut 39 and turning the shaft 32 upon its axis.

The guiding device is adapted to handle all kinds of yarn, such as cotton, rayon, silk, wool, etc.

The yarn guiding jaws may face horizontally inwardly or outwardly, upwardly or downwardly.

It is to be understood that the forms of my invention herewith shown and described are to be taken as preferred examples of the same, and that various changes in the shape, size and arrangement of parts may be resorted to without departing from the spirit of my invention or the scope of the subjoined claims.

Having thus described my invention, what I claim is:

1. A yarn guiding device, comprising an annular floating yarn guiding member, a companion yarn guiding member, one member being arranged within the other member, the outer member having yarn engaging parts, and adjustable means to draw the parts together to regulate the tension upon the yarn.

2. A yarn guiding device, comprising a relatively stationary yarn guiding ring, a floating casing receiving the ring and including opposed yarn engaging jaws, and adjustable means to draw the jaws toward the yarn guiding ring to vary the tension upon the yarn.

3. A yarn guiding device, comprising a casing including casing sections having opposed yarn engaging jaws, adjustable means to draw the jaws together, a support for the casing, and a floating yarn guiding ring arranged between the jaws.

4. A yarn guiding device, comprising a casing including annular casing sections, said casing sections having opposed inner and outer jaws, a connecting ring arranged between the outer opposed jaws, adjustable means connecting the casing sections to draw the inner jaws together, a floating yarn guiding ring arranged between the inner jaws, and means to support the connecting ring.

5. A yarn engaging device, comprising a casing including casing sections, said casing sections including opposed webs having inner jaws and outer jaws, adjustable means connecting the webs to draw them together, a connecting ring held within the outer jaws, a rod secured to the connecting ring, adjustable means engaging the rod to pivot the same so that it may be swung vertically and be turned upon its longitudinal axis, and a floating yarn guiding ring arranged between the inner jaw.

6. A yarn guiding device, comprising a yarn guiding ring, supporting means connected with the yarn guiding ring, opposed yarn engaging jaws receiving the yarn guiding ring between them, and adjustable means to draw the jaws together to vary the tension upon the yarn.

7. A yarn guiding device, comprising a casing having a pair of opposed inner jaws and a pair of opposed outer jaws, a supporting ring arranged between the outer jaws and having an opening formed therein, said casing having a transverse yarn threading slit adjacent to the opening in the supporting ring, and a continuous floating yarn guiding ring arranged between the inner jaws.

8. A yarn guiding device, comprising a casing having opposed yarn engaging jaws, said casing having a transverse yarn threading slit, portions of the casing overlapping at the slit, a floating yarn guiding ring arranged between the jaws, and adjustable means to draw the jaws together to vary the tension on the yarn.

9. A yarn guiding device, comprising a casing having opposed yarn engaging jaws, a yarn guiding ring arranged between the jaws and forming with the jaws a space for the passage of the yarn, and adjustable means to draw the jaws together to regulate the tension upon the yarn.

10. A yarn guiding device, comprising opposed casing sections provided at corresponding edges with opposed jaws and at opposite corresponding edges with opposed jaws, a ring arranged within the first named opposed jaws, a yarn guiding ring arranged within the second named opposed jaws and forming therewith a space for the passage of the yarn, and means connecting the casing sections and holding the first named jaws upon the first named ring.

11. A yarn guiding device, comprising opposed annular casing sections, said casing sections including webs and opposed jaws carried by the corresponding edges of the webs and opposed jaws carried by the opposite corresponding edges of the webs, a ring arranged between the first named opposed jaws, a thread guiding ring arranged between the second named opposed jaws and forming therewith a space for the passage of the yarn, and adjustable means connecting the webs to draw them together.

LINTON L. JONES.
